UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,237.

Specification of Letters Patent. Patented June 18, 1918.

Application filed July 5, 1912. Serial No. 707,666.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 This invention relates to combined type-writing and computing machines, such for instance as illustrated in the pending application of Walter Wright and Gustave O. Degener, No. 543,603, filed February 12, 1910, 15 and my Patents No. 990,238, dated April 25, 1911, and No. 1,020,082, dated March 12, 1912.

In such machines, the numeral keys are connectible to the computing mechanism for determining the extent of rotation thereof, 20 and as therein disclosed, the keys are normally disconnected from the computing mechanism whenever it is desired to write figures without effecting computation thereof.

One of the objects of the present invention is to facilitate the operation of the machine by relieving the mind of the operator from the task of remembering to connect and disconnect the keys and the computing mechanism at every line of writing, as for instance in the making of a bill, where it is desired to compute only the numbers written on a given column of the work sheet. It is a special object of the present invention to arrange the mechanism so that it may be readily altered to suit any particular arrangement of work which may be on hand for the time being. For this purpose, the carriage of the typewriter is arranged to automatically effect connection between the numeral 35 type keys and their connection to the computing devices, whenever the carriage reaches the desired position for computation, and this position may be readily altered by the shifting of the member automatically controlling said connection, or by substituting a 40 new member.

The devices by which the carriage controls the connection of the figure keys to the computing mechanism preferably include a 50 tappet or device adjustable along the carriage itself, so as to determine at what point in the line of writing computation shall begin. This tappet, which may be mounted upon a column stop bar, and which may itself also serve as a column stop, engages and

operates a cam or lever, which is connected to the key connections, so as to make or break the latter, and said cam is adjustable preferably by screws, so that it may be extended or shortened, or another one substituted therefor of a different operative length, so as to hold the keys connected to the computing mechanism during any desired portion of the run of the carriage in letter-feeding direction.

65 Other features and advantages will hereinafter appear.

In the accompanying drawings,

Figure 1 is a side elevation of an Underwood typewriting and computing machine 70 having the present improvements applied thereto.

Fig. 2 is a perspective view, showing the connections between the keys, computing mechanism, and their controlling mech- 75 anism.

Fig. 3 is a detail front view of the manual means for connecting the keys to the computing mechanism.

Fig. 4 is a view of the controlling cam or 80 lever, and Figs. 5 and 6 are details thereof.

Alphabet key levers 1 and numeral key levers 2 depress bell cranks 3 to swing type bars 4 upwardly and rearwardly to cause type 5 to strike against a platen 6 mounted 85 in a carriage 7, which carriage is drawn in letter feeding direction by a spring barrel 8. Said carriage is controlled at its letter-feeding movement by means of an escapement wheel 9 carrying a pinion 10, which meshes with a rack 11 on said carriage, said escapement wheel 9 being governed by dogs 12 operated by heels 13 on the type bars, through intermediary of a universal bar 14.

As set forth in said application No. 543,603, a transverse horizontal endwise movable rack or bar 15 is employed for the purpose of connecting and disconnecting the computing devices from the type-operating key levers 2. Links 16, one for each 95 numeral key lever, are dropped through holes 17 in said disconnecting bar 15, and are connectible at their lower ends by hooks 18 to catches 19 on the numeral key levers 2, and are pivoted at their upper ends 20 to bell cranks 21, (which will be presently described) for controlling the computing devices.

100 Whenever a numeral key lever is depressed, the link 16 is pulled down and the 110

computing device is operated. By shifting the bar 15 to the left in Fig. 2, the links 16 are swung free of the catches 19, and then the numeral keys 2 may be depressed to cause their types to operate without computing. The disconnecting bar 15 may be operated in any suitable manner, as for example that shown in said application, wherein said bar has a pin or pivot 22 engaging a slot in the lower end of an upstanding lever 24, which is pivoted between its ends at 25 upon a fixed support. By swinging said lever 24 to and fro, the bar 15 connected thereto, may be caused to disengage and reengage the links 16, and the numeral key levers 2.

A slot 26 in the upper end of the lever 24 is engaged by a pin or pivot 27, the latter projecting rearwardly from the top of the uppermost arm of a four-armed lever 28, the latter being rotatable upon a central pivot 29 upon a fixed support or plate 31. Said pin 27 projects through an opening 30 in the plate 31, on which the pivot 29 may be mounted. The lever 24 is mounted at the rear of said plate 31, while the four-armed lever 28 is in front thereof.

Upon said pin 27 is loosely pivoted by means of a hub 32, a crank or arm 33, carrying a handle 34. To the latter is attached the lower end of a draw spring 35, the upper end thereof being caught upon a fixed pin 36 on said plate 31. Said spring holds a pin 37 on said lever 33 up against a pin 39, as shown in Fig. 3, projecting from the left end of cross arm 40 of said four-armed lever, and thereby holds the latter in said Fig. 3 position, and consequently holds the disconnecting bar 15 in position to hold the links 16 in operative engagement with the key levers 2.

By means of the handle 34, the lever 33 is swung from the left-hand position seen in Fig. 3 to the position shown in Fig. 2, which, when viewed from the front of the machine, is the right-hand position, and the spring 35 holds them there with the links 16 disconnected from the key levers 2.

The position of the lever 33 on either side of the pivot 29 of the four-armed lever 28 may be determined by the lever 44 pivoted at 45 to the lowermost arm of the four-armed lever 28 and having a pin 43 engaging in a slot 46 provided in the rearmost portion of the arm 33, which is duplex. It will thus be seen that when the parts are in the position shown in Fig. 2, the hook links 16 will be normally disconnected from the latch 19 on the key levers 2, but may be connected thereto by pulling down on a link 41, which will temporarily stretch the spring 35 and swing the cross lever 28, without, however, changing the position of the arms 33 and 45 relatively to each other. Such a rocking of the cross lever 28 by the

link 41 will naturally draw the hooks 18 of the links 16 temporarily into engagement with the catches 19 of the key levers 2, so that the numeral keys would be temporarily connected to actuate the computing mechanism in spite of the fact that the controlling mechanism is manually adjusted for disconnection of the numeral keys from the computing mechanism. Said link 41 is pivoted to an arm 47 on a rock shaft 48, carrying a second rock arm 49, through which rock shaft the automatic connection of the numeral keys with the computing mechanism is brought about.

A stop 50 on a rack bar 51 on the carriage 7 of the typewriter, is arranged to control said connection through said rock shaft 48 by means of an extension 52 on said stop, which extension is arranged to strike a lever 53 on the framework of the tabulating mechanism. Said lever 53 includes an arm 54, joined to the rock arm 49 by means of a link 55, through which arm it operates said rock shaft 48.

The upper end of the lever 53 is shown as 90 formed of two shiftable and detachable cam plates, arranged to overlie each other. One of these plates 57 lies against the upper face 56 of said lever 53, and is adjustable thereon by means of screws 58, and said member 95 comprises a bent portion 59, arranged to bear against the extension 52 on said stop 50, during a portion of the travel of the typewriter carriage. As will be seen from Fig. 2, this cam is the one which connects 100 the keys to the indexing devices while writing the units digit and the digits adjacent thereto. The ends 60 of said face 59 are beveled to form cam surfaces, so that the lever 53 will be swung outward as it strikes 105 said extension 52.

A second cam member 61 is arranged to lie against said first cam member and be also held in place by screws 58, and has a face 62 arranged to form a straight line 110 with the face 59 of the cam member 61, and is beveled to form faces 60 like those on the plate 57. It will be observed that the cam 61 may be adjusted without disturbing the cam 57, thus providing means whereby the 115 computing zone may be varied in length without having to relocate the units digit position each time. When the two cam members coincide they cover a relatively small portion of the travel of said extension 120 52, but they may be so set, as to cover a greater portion of said travel by means of the combined length of their faces 59 and 62. The space over which the numeral keys control the computing is thus varied by the 125 setting of these cam members. In other words, the two cam plates may be called an "adjustable zone control" in that they determine the extent or magnitude of a computing zone, for when they are not in en- 130

gagement with a tappet or stop 50 the computing mechanism will be silenced by being disconnected from the numeral keys.

The computing mechanism may be of any desired form, and is herein illustrated as shown in said Wright and Degener application aforesaid. As shown in said application, the links 16 are connected to bell cranks 21, and links 63 extend from the latter to levers 64, which operate dogs 65, to thrust out index pins 66, provided upon a computation or primary escapement wheel 67 forming part of an indexing mechanism, said pins being adapted to engage a four-armed pinion 68, which is fixed to a secondary escapement wheel 69. The latter is controlled by dogs 70 upon a rock shaft 71, the latter connected by a link 72 and lever 73 to a universal plate 74 operable by arms 75 on all the levers 64, the latter having fixed fulcrum points 76. The pins 66 are detained in their effective or ineffective position by the usual coil-spring band 67^a encircling the wheel 67.

Whenever a lever 64 is operated by this key, a pin 66 is thrust out toward the left in Fig. 2, so as to be the next pin to engage the pinion 68. At the same time, the dogs 70 are rocked, and the secondary escapement wheel 69 is permitted to rotate, the main computation wheel 67 being under constant rotational torque, and turned to an extent dependent upon the position of the last pin projected by its jack 65.

Power for wheel 67 is derived from a constantly rotating motor 77, having a friction clutch, not shown, to which is secured a pinion 78 meshing with a pinion 79 on a shaft 80, the latter having a pinion 81 meshing with a pinion 82 to which is fixed a pinion 83, meshing with a pinion 84 fixed to said computation wheel 67.

As the pins 66 pass beyond the pinion 68, they are restored to normal position by a wiper or cam, not shown. A train of computing mechanism extends from said wheel 67 and includes said pinions 84, 82, 83, and also a pinion 85, meshing with pinion 83, and fixed upon a shaft 86. Said shaft 86 carries a pinion 87 meshing with a pinion 88 on a shaft 89, the latter carrying at its upper end a pinion 90 meshing with a pinion 91 in a totalizer 92. Said totalizer carries a master wheel, not shown, and computing mechanism, and said totalizer is carried along with the typewriter carriage 7, by means of an arm 93 fast thereon. Therefore, it will be seen that the totalizer will bear a constant relation to any stop 50 of the rack bar 51, and by proper positioning of said stop, the extension 52 of any stop will connect the numeral keys to the computing mechanism at any desired point in the travel of the typewriter.

For tabulating purposes, the stops 50 on the typewriter are arranged to coöperate

with a set of decimal or other tabulator plungers 94 upon the rear ends of levers 95 fulcrumed at 96, and carrying keys 97 at their forward ends. Whenever a key 97 is depressed, its rod 94 is raised, and a lug 98 thereon lifts a small universal bar 99 which turns upon a pivot 100, and has an arm 101, the latter connected by a link 102 to a lever 103, the lever having a roll 104 to lift the rack 11 from the pinion 10, so that the carriage 7 can run freely along until arrested by the engagement of the elevated stop 94 with the next carriage stop 50, this being the usual operation of the Underwood decimal tabulating mechanism. Any of said stops 50 may be, as above described, provided with an extension 52 to coöperate with the cams on the lever 63, and control the connection of the numeral keys with the computing mechanism.

The lever 53 may be limited in its throw by a headed screw 105 carrying an adjustable nut 106, and to keep it ineffective and to prevent rattling is normally held outwardly against the head of said screw 105 by a spring 107, when the handle 34 is positioned to connect the numeral keys to the computing mechanism. Said spring 107 must be materially weaker than spring 35.

In the embodiment of my invention herein illustrated, one cam member 57 comprises two slots 108 and 109, so that this member may be held fast in any adjusted position while the other cam member 61 is removed or adjusted. The cam member 61 may comprise only one slot 110, and this slot and slot 109 should be long enough so that the outer cam member 61 may always be held in position by two screws 58 or other alining members.

Variations may be resorted to within the scope of the invention, and portions of the improvements may be used without others.

Having thus described my invention, I claim:

1. In a combined typewriting and computing machine, the combination with a letter-feeding carriage and computing mechanism, of zone-controlling means for determining the effectiveness of said computing mechanism, said zone-controlling means comprising a tappet, and an actuator to be operated by said tappet, said actuator including a pair of members overlapping and adjustable lengthwise to each other to provide a variable bearing surface for said tappet, relative movement between said tappet and said actuator being effected by connecting one of said parts for movement with said carriage.

2. In a combined typewriting and computing machine, the combination with a letter-feeding carriage and computing mechanism, of zone-controlling means for determining the effectiveness of said computing

- mechanism, said zone-controlling means comprising a tappet, and an actuator to be operated by said tappet, said actuator including a cam and a longitudinally adjustable extension for said cam to provide an extensible cam surface for said tappet, relative movement between said tappet and said actuator being effected by connecting one of said parts for movement with said carriage.
- 5 10. In a combined typewriting and computing machine, the combination with a letter feeding carriage, computing mechanism, and numeral keys, of a rack bar, means including a lever governing the connection between said numeral keys and computing mechanism, a stop adjustable on said rack bar arranged to move said lever to connect said keys to said mechanism at a column determined by the point where the stop is located, and a part adjustable on said lever to vary the number of letter spaces over which said connection is operative.
- 15 11. In a combined typewriting and computing machine, the combination with a letter feeding carriage, computing mechanism, and numeral keys, of a rack bar, means including a lever governing the connection between said numeral keys and computing mechanism, a stop adjustable on said rack bar arranged to move said lever to connect said keys to said mechanism at a column determined by the point where the stop is located, a cam on said lever to move it from said stop, and an adjustable extension of
- 20 25 30 35 40 45 50 55 60 65 70 75 80 85 90 95 100 105 110 115 120 125 130
- mechanism, of zone-controlling means for determining the effectiveness of said computing mechanism, said zone-controlling means comprising a tappet, and an actuator to be operated by said tappet, said actuator including a longitudinally adjustable cam and a longitudinally adjustable extension for said cam to provide an extensible cam surface for said tappet, relative movement between said tappet and said actuator being effected by connecting one of said parts for movement with said carriage.
8. In a combined typewriting and computing machine, the combination with a letter-feeding carriage and computing mech- 80
- anism, of zone-controlling means for determining the effectiveness of said computing mechanism, said zone-controlling means comprising a tappet, and an actuator to be operated by said tappet, said actuator including a longitudinally adjustable cam and a longitudinally adjustable extension for 85
- said cam to provide an extensible cam surface for said tappet; said extension being adjustable without disturbing the adjustment of said cam, relative movement between said tappet and said actuator being effected by connecting one of said parts for movement with said carriage.
9. The combination with a computing 95
- mechanism, of a traveling element, computing zone-controlling means for determining the effective period of activity of said computing mechanism, and a tappet carried by said traveling element for operating said zone-controlling means, said zone-controlling means including a pair of members overlapping and adjustable lengthwise of each other so as to vary their effective length and bearing surface with respect to 105
- said tappet.
10. The combination with a computing mechanism, of a traveling element, computing zone-controlling means for determining the effective period of activity of said 110
- computing mechanism, and a tappet carried by said traveling element for operating said zone-controlling means, said zone-controlling means including a pair of members overlapping and adjustable lengthwise of 115
- each other so as to vary their effective length and bearing surface with respect to said tappet, said zone-controlling means including means for adjusting and locking one of said overlapping members without disturbing the adjusted position of the other.
11. The combination with a computing mechanism, of a traveling element, computing zone-controlling means for governing the effective period of activity of said computing mechanism, and a tappet carried by 120
- said traveling element for actuating said zone-controlling means, said zone-controlling means including a pair of plates slidably connected together so as to be adjust- 125
7. In a combined typewriting and computing machine, the combination with a letter-feeding carriage and computing

able to vary the extent of effective bearing surface exposed to contact with said tappet.

12. In a computing machine, a zone-determining actuator comprising a pair of 5 camming members mutually contributing to form an extended cam surface of variable extent, said members being relatively adjustable to vary their effective working surface.

10 13. The combination with a computing mechanism, of a traveling element, and means controlled in its operation by the movement of said traveling element for determining the effectiveness of said computing mechanism, said determining means including a vibratory lever, a spring tending to hold said lever out of the path of movement of said traveling element, a stronger spring to overcome said first-mentioned 20 spring and bring said vibratory lever into the path of movement of said traveling element, so that it may be engaged and actuated thereby, and means for adjustably limiting the effective throw of said vibratory lever 25 under the influence of said springs.

14. The combination with a computing mechanism, of a traveling element, zone-controlling means actuated by said traveling element for governing the effective 30 periods of said computing mechanism, said zone-controlling means including a vibratory lever having an opening therein, and a headed screw extended through said opening for limiting the extent of vibration of 35 said lever.

15. The combination with a computing mechanism, of a traveling element, zone-controlling means actuated by said traveling element for governing the effective 40 periods of said computing mechanism, said zone-controlling means including a vibratory lever having an opening therein, a headed screw extending through said opening for limiting the extent of vibration of 45 said lever, and a spring normally tending to hold said lever in its ineffective position.

16. In a combined typewriting and computing machine, the combination with numeral keys and a traveling carriage, of a 50 tappet on said carriage, an adjustable cam extending part way along the travel of said tappet, computing mechanism, links extending from said keys to control said computing mechanism, and means for disconnecting 55 said links at said keys by making said tappet effective on said cam in the travel of said carriage.

17. In a combined typewriting and computing machine, the combination with nu-

meral keys and a traveling carriage, of 60 a tappet on said carriage, an adjustable cam extending part way along the travel of said tappet, computing mechanism, links extending from said keys to control said computing mechanism, means for disconnecting 65 said links at said keys by making said tappet effective on said cam in the travel of said carriage, and a handle for connecting said links to said keys independently of said tappet and cam.

18. In a combined typewriting and computing machine, the combination with numeral keys and a traveling carriage, of a tappet on said carriage, a cam extending part way along the travel of said tappet, 75 computing mechanism, an extension of said cam adapted to be adjusted to vary the effective length of the cam, links extending from said keys to control said computing mechanism, and means for disconnecting 80 said links at said keys by making said tappet effective on said cam in the travel of said carriage.

19. In a combined typewriting and computing machine, the combination with numeral keys and a traveling carriage, of a tappet on said carriage, a cam extending part way along the travel of said tappet, computing mechanism, an extension of said cam adapted to be adjusted to vary the 90 length of the cam, screws for so adjusting it, links extending from said keys to control said computing mechanism, means for disconnecting said links at said keys by making said tappet effective on said cam in 95 the travel of said carriage, and a handle for connecting said keys independently of said tappet and cam.

20. In a combined typewriting and computing machine, the combination with a letter-feeding carriage, computing mechanism and typewriter numeral keys, of a traveling carriage, a tappet adjustable on said carriage, indexing devices forming part of said computing mechanism, means including a lever for connecting said keys to said indexing devices, a cam on said lever adapted to be operated by said tappet, and a second cam adjustable along said first-mentioned cam without disturbing the adjustment of said first-mentioned cam to determine how long the lever shall be effective to connect said keys to said devices.

GUSTAVE O. DEGENER.
